Inventor:

Edra Edwards,

By Thomas G. Drury, Atty.

UNITED STATES PATENT OFFICE.

EZRA EDWARDS, OF WEBSTER CITY, IOWA.

EGG-TESTER.

SPECIFICATION forming part of Letters Patent No. 595,292, dated December 14, 1897.

Application filed May 11, 1897. Serial No. 636,119. (No model.)

To all whom it may concern:

Be it known that I, EZRA EDWARDS, a citizen of the United States of America, and a resident of Webster City, in the county of 5 Hamilton and State of Iowa, have invented a new and useful Egg Separator and Candler, of which the following is a specification.

The object of this invention is to provide improved means for separating eggs from packing material—such as oats, chaff, bran, or sawdust—and at the same time interpose the eggs between the eyes of the operator and a strong artificial light in order that the transparency of the eggs may be tested and an 15 opinion formed by the operator as to the age and condition of the edible portions of said eggs.

My invention consists in the construction, arrangement, and combination of elements 20 hereinafter set forth, pointed out in my claims, and illustrated by the accompanying drawings, in which—

Figure 1 is a side elevation of the complete machine. Fig. 2 is a sectional plan of the machine on the indicated line $x-x$ of Fig. 1. Fig. 3 is a sectional elevation of a portion of the machine on the indicated line 1 1/2 of Fig. 2. Fig. 4 is a detail perspective of a candle-holder and candle detached from the machine.

30 In the drawings, the letters A B C D E designate portions of a supporting-frame arranged, so shaped, and connected as to sustain the operative parts of my machine and at the same time provide a table or stand a , which 35 may be employed to hold an egg case or receptacle. (Not shown.) The upper portion A of the frame is rectangular in plan view, and a four-sided hopper e is fixed thereto and depends therefrom. An opening is formed 40 at the convergence of the sides of the hopper e , and a door b is horizontally mounted for reciprocation in bearings fixed to the hopper sides and is arranged to traverse the said opening. A cylinder or light-chimney 10 is 45 located within the lower portion of the hopper e and is supported by legs resting on the upper surfaces of the hopper sides. A removable section or plate M is formed in one side of the chimney 10 , and a bracket 11 is 50 fixed to and projects inwardly from said plate and is further secured thereto by a brace 12 . A socket 13 is fixed to and rises from the outer

end portion of the bracket 11 , and a candle G is removably and replaceably mounted in said socket. An opening f is formed in the 55 hopper e , through which access is had to the interior of the hopper to remove and replace the plate M and candle-bracket. The opening f may be closed by a sliding door arranged for reciprocation in bearings fixed to 60 the side I of the hopper in which said opening is located. A receptacle of some sort may be placed below the door b to receive the egg-packing material from the hopper. A rectangular frame H is fitted within the part A 65 of the supporting-frame, and a section or piece of wire cloth or screen F is fixed to and stretched between the lower edges of said frame H . An arched sheet-metal cover 14 is fixed at its margins to the lower edges of the 70 frame H and is provided with handles $g-g$, whereby said cover, the frame H , and the screen conjunctively may be removed from the supporting-frame. An opening is formed in the cover 14 , through which access is had 75 to the interior of the machine, and said opening is closed when the machine is not in use by a door d , vertically positioned for reciprocation in bearings 15 , fixed to said cover.

In practical use I empty a box or case of 80 eggs and the material in which they are packed upon the screen through the opening in the cover, and the packing material sifts through the screen, runs into the lower portion of the hopper, and is drawn off by the 85 opening of the door b . I then uncover the opening f and insert the plate M and candle-bracket in the chimney 10 and light the candle G . I then close the opening f and door b , and looking through the opening in the 90 cover I can see the eggs interposed between my eyes and the artificial light of the candle and judge of the comparative freshness of the eggs. The eggs are removed from the screen through the opening in the cover. 95

I claim as my invention—

1. An egg tester and separator comprising a frame adapted to support a hopper, a table at one end of the frame adapted to support a basket or egg-case, a hopper fixed in the frame 100 and provided with an opening at its bottom and one in its side, means for closing said openings, a wire screen fitted in the top of the hopper, a candle-holder detachably con-

nected with the open bottom of the hopper and a cover fitted over the top of the hopper and frame and provided with an opening at its central portion, arranged and combined to 5 operate in the manner set forth for the purposes stated.

2. In a device of the class described, the combination of the supporting-frame, a hopper in said frame, an artificial-light-producing means in the bottom of said hopper, a screen in the upper portion of said hopper, a cover over the screen and a gate in the bottom 10 of the hopper.

3. In a device of the class described, the combination of a supporting-frame, a hopper 15 in said frame, a lamp in said hopper, a frame H in the upper portion of said hopper, a screen fixed to said frame H, an opaque cover fixed to the frame H and arched above the screen, means of access to the interior of the 20 cover and a gate in the bottom of the hopper.

EZRA EDWARDS.
